UNITED STATES PATENT OFFICE.

CHARLES W. THOMAS, OF CLEVELAND, OHIO, ASSIGNOR TO THE THOMAS STOKER COMPANY, OF CLEVELAND, OHIO, A CORPORATION OF OHIO.

GRATE FOR STOVES AND FURNACES.

Application filed January 9, 1924. Serial No. 685,075.

The present invention relates to stoves and furnaces, and more particularly to an improved grate for use in connection with the same.

5 One object of the invention is to provide a grate which is adjustable so as to open and close to the desired extent within practical limits draft openings, and also ash sifting or removing openings so that the fuel supported 10 on the grate may be provided with the necessary draft for causing the consumption of the fuel either rapidly or slowly as desired and to also distribute the draft uniformly throughout the body of fuel.

15 Another object of the invention is to provide a grate made up of a plurality of relatively movable fuel supporting sections which are interconnected to limit their relative movements, whereby shaking down of 20 the ashes may be effected.

A further object of the invention is to provide an adjustable grate of this character which is designed to separate the body of fuel in a uniform manner so that the fuel may be 25 supported in a substantially conical mass to more evenly distribute the fuel over the grate and thus insure the even and complete consumption of the fuel and the uniform removal of the ashes as the fuel is being consumed.

30 The invention still further aims to provide a grate of this character which is composed of a plurality of telescoping sections one of which is adapted to be moved vertically, and the sections are provided with means for engaging the adjacent sections in consecutive order and one at a time during the movement of the first section.

Other objects of the invention will be apparent to those skilled in the art to which my 40 invention relates from the following description, taken in connection with the accompanying drawing.

In the drawings,

45 Figure 1 is a vertical section taken through the lower end of a stove or furnace constructed according to the present invention with an adjustable grate.

50 Figure 2 is a horizontal section taken through the same immediately above the grate and substantially on the line 2-2 of Figure 1.

55 Figure 3 is a sectional view similar to Figure 1 and showing the grate in open and raised position.

Figure 4 is a fragmentary enlarged section taken horizontally beneath the grate on the line 4-4 of Figure 1, and looking upwardly toward the bottom of the grate, and

60 Figure 5 is a fragmentary enlarged sectional view taken through one side portion of the grate substantially on the line 5-5 of Figure 4.

65 Referring to the drawings, 10 indicates the outer casing of a stove or furnace, which for illustrative purposes, is shown as a furnace of the hot air type suitable for heating purposes. The casing 10 is provided with a combined fire pot and ash pit casting 11, preferably having the usual inwardly extending lugs 12 for supporting a grate and provided at its front side with a housing or boxing 13, which extends through the front wall of the casing 10 to permit the removal of ashes and access to the grate adjusting and shaking 70 mechanism to be later referred to. The outer end of the housing 13 may be closed by a suitable door (not shown). The upper portion of the casing 10 is provided with an opening, 75 adapted to be closed by a door, so that fuel may be supplied to the grate and fire bed.

80 The furnace or stove 10 is provided with a bottom 14 arranged to close the lower end of the furnace and to support the casting 11 and may be integral therewith, as shown. 85 The bottom 14 has an air inlet passage 15 which communicates with the chamber between the casing 10 and the casting 11. The above parts are merely conventional and are illustrated and described merely for the purpose of showing one device to which the grate of the present invention may be applied.

90 The grate is composed of a center piece 16, 95 preferably of circular shape, and a plurality of concentrically arranged ring portions 17 arranged about the center piece 16 and being enclosed in an outer ring part 18 adapted to rest upon the lugs 12 in the stove or furnace body 11. The inner or center piece 16 and the rings 17 may be arranged in a horizontal plane or disposed relative to each other above or below that plane to increase combustion, as desired; but preferably these elements are arranged to be moved upwardly. Arranged 100 in the top of the ash pit of the casting 11 and closely beneath the lugs 12 is a spider 19 having a raised hub 20 and radially extending arms 19^a carried by the hub. The arms 19^a 105 may be integrally or otherwise suitably sup-

ported upon the inner wall of the casting 11. The hub 20 has a vertical opening therethrough in axial alignment with the center piece 16 of the grate and through which is slidably mounted a tubular or hollow post 21, the upper end of which is suitably connected to the under side of the center piece 16 of the grate. The hollow post 21 is slidably and rotatably mounted over a spindle or standard 22 which is mounted on a foot piece 23 resting on the bottom 14 of the furnace and which is adapted to guide the post 21 in its vertical movements.

For vibrating and turning the post 21, the latter has pivoted to it a forked hand lever 24 which projects outwardly through the boxing 13 a distance sufficient to be readily grasped by the operator. A link 25 is rotatably mounted at one end on the spindle, preferably between the lower end of the post 22 and the foot piece 23, and at its other end is pivoted to the hand lever 24 intermediate the ends thereof so as to serve as a movable fulcrum upon which the lever 24 may be swung to raise and lower the tubular post 21 on the spindle and to thus raise and lower the center piece 16 of the grate.

The outermost ring 18 comprises a flat annular body with radially extending lugs or teeth 26 which are adapted to overlap and seat upon the inwardly extending lugs 12 of the stove casting 11. The intermediate rings 17 may be of any desired number to fill the space between the outer ring 18 and the center piece 16. Each ring 17 comprises an annular body having a flat upper surface and provided around its outer edge with radially extending teeth or lugs 27 adapted to movably fit within the inner marginal edge of the outer adjacent ring, to form spacers between the rings and bearing surfaces for them to slide or telescope on. Certain of the teeth 27 are provided with depending members 28 having hooks 29, which project outwardly into position beneath the outer adjacent ring so that when one ring 17 is elevated to an extent sufficient to bring the hook 29 of its members 28 against the next outer adjacent ring, the latter ring is then elevated with the ring 17. The depending members 28 are of the desired length to provide a vertical space between adjacent rings when the inner ring is elevated out of the horizontal plane of the outer ring and to permit the passage of air upwardly between the rings and also permit the falling of ashes downwardly between the rings when the latter are vibrated. The teeth 27 which are disposed between those teeth which carry the hooks 29, are provided upon their under sides with depending ribs 30 which are of less length than the depending members for the hooks 29, but are of such length that when any or all of the rings are lowered, the ribs 30 adjacent to and in alignment with the spider 19 may rest on the arms

of the latter, and thereby support the lowered grate rings in a horizontal position.

It will be noted, particularly from Figures 1 and 4 that the outer side walls 31 of the rings, between the teeth thereof, are sloped downwardly and inwardly, this construction being preferable so as to direct air currents upwardly and outwardly in a direction toward the flaring inner wall of the fire box in the casting 11. Thus the air which is admitted up through the rings, and between the rings when raised, is spread or deflected outwardly in its passage upwardly through the grate.

For the purpose of interlocking the rings and center piece so as to turn with the hollow post 21 when the handle 24 is moved from side to side or oscillated about the spindle 22, the outer ring 18 and the intermediate rings 17 are provided at spaced points with depending lugs 32 which are adapted to be engaged by the sides of the hooks 29 carried by the next adjacent inner ring, so that if the center section is oscillated by the handle 24 the hooks 29 on each ring will engage the lugs 32 on an adjacent ring to effect oscillatory movement of the latter.

The center piece 16 forms a cap for the upper end of the hollow post 21 and it preferably has a convex upper surface which rises above the plane of the grate rings when the latter are in their lower position. The center piece 16 is provided at its marginal edge with radially extending teeth 34 which are adapted to slidably fit within the inner marginal edge of the adjacent ring 17. Certain of the teeth 34 are provided with depending members 28a having hooks 29a so as to interlock with the adjacent ring 17 when the center piece 16 is raised to or beyond a predetermined height.

In use, fuel is placed upon the grate in the ordinary manner, and when it is desired to permit additional air to pass up through the grate it is only necessary to depress the outer end of the hand lever 24 for moving the hollow post 21 upwardly upon the spindle 22 and to raise the center piece 16, first to an extent sufficient to engage the hooks 29a of the center piece with the first ring 17. This provides a plurality of vertical air passages or slots between the center piece 16 and the ring 17 and between the depending members 28a and hooks 29a of the center piece 16. Should further draft be required the handle 24 is further depressed so as to further raise the center piece 16 and through it innermost ring 17 until the next outer ring 17 is caught by the hooks 28 of the first ring when further air is admitted between the two intermediate rings 17. The handle 24 may be further depressed, if desired, until all of the intermediate rings have been elevated. The wall of the casting 13 may be provided at one side with a rack 35 to engage the handle 24 so that

the latter may be locked at different elevations to hold the grate extended to the desired degree.

36 indicates devices carried by each grate member and arranged to engage an adjacent member when it is moved toward the horizontal or common plane position so that when the operated member is moved it will act on and through each succeeding member or 10 members to move them. I preferably provide two or more engaging devices 36 on each member and space them around it. The devices may comprise outwardly extending lugs integrally connected to the outer edge of each 15 member and disposed so as to overlie the next adjacent outer member and hence engage therewith as the member moves downwardly.

As shown in Fig. 1, the grate rings fit together in compact relationship when in the 20 horizontal or lowered position, on the spider 19, thereby substantially closing the openings or space between the rings and preventing active combustion, so that burning of the fuel can be controlled. By raising one or more 25 rings a greater or lesser height, any desired adjustment thereof can be made to permit the desired amount of air to pass upwardly through the fire bed, between the rings, to increase the combustion; Fig. 3 showing all the 30 rings, except the outer one, raised. When one or more rings are raised, the fuel disposed on the ring or rings which are raised and the next outer one and the fuel disposed across the space between such rings, will be 35 spread or separated, so that air may freely pass or circulate therethrough between the rings and through the fire bed.

By reciprocating the lever 24 and causing 40 movement of the grate rings relatively to each other upwardly and downwardly, a shaking of the fire bed can be effected. Such action can also be effected by oscillating the handle 24 about the spindle 21 or by imparting to it both reciprocatory and oscillatory 45 movements, as desired.

The post 21 is connected to the inner grate member and it and each ring are provided with depending hook carrying members on their outer edges. It will be obvious that 50 these parts could be arranged on the inner edges of the rings and the outer ring raised first and through it the next inner ring, and so on, without departing from the principle of the invention. To those skilled in the art 55 to which this invention relates many alterations in construction and widely differing embodiments and applications of my invention will suggest themselves without departing from the spirit and scope thereof. My disclosures and the description herein are 60 purely illustrative and are not intended to be in any sense limiting.

What I claim is:

1. A grate comprising a plurality of relatively movable sections, means for moving

one of the sections, interlocking means carried by the sections and arranged for consecutively moving the sections upon the movement of one thereof in one direction, and separate means carried by said sections for 70 consecutively moving them upon the movement of the operated section in the opposite direction.

2. A grate comprising a plurality of annular sections and a center section, means 75 for moving the center section, interlocking means carried upon the center section and the intermediate sections for engaging the adjacent outer sections consecutively as the center section is operated in one direction, 80 and separate means carried by the respective sections for engaging each adjacent outer section as the center section is operated in the opposite direction.

3. A grate comprising a center section, a 85 plurality of ring sections arranged thereabout, means for moving the center section, hook members carried upon the center section and said ring sections and arranged to interlock with the adjacent outer sections 90 consecutively as the sections are operated in one direction, and separate means carried by the respective sections for engaging each adjacent outer section as the center section is operated in the opposite direction. 95

4. A grate comprising a center section and a plurality of relatively movable ring sections arranged thereabout, said sections having radially extending teeth providing air 100 passages there-between and between the sections, and having depending ribs on the teeth, hooks carried by the sections and spaced downwardly therefrom adapted to interlock with adjacent outer sections as the center section is operated in one direction, whereby 105 to expose said ribs to form air passages between the sections, separate devices on each of said sections arranged to engage the next outer section to move the same when said center section is operated in the opposite direction, and means for moving said center section. 110

5. A grate comprising a center section, and a plurality of relatively movable ring sections arranged concentrically thereabout, said sections having radially extending teeth providing air passages therebetween and having depending ribs on the teeth for engaging the inner marginal edges of the ring sections for maintaining the latter in their relative positions, means for moving the center section, and hooks carried upon the center and ring sections for consecutively engaging the outer sections as the center section is operated to increase the size of the space between the sections. 115 120 125

6. A grate comprising a plurality of concentric toothed sections provided with depending spacing teeth for holding the sections in concentric relation and providing 130

air spaces therebetween, a center section, and means for raising the center section, and follower hooks carried by the sections adapted to engage adjacent sections for consecutively elevating the sections as the center section is raised.

7. A grate comprising a plurality of concentric sections having radial teeth and depending supporting ribs on the teeth, a spider supported beneath the section for engaging said ribs to hold the sections when in the lowered position, means for elevating the center section, and hooks carried by the sections projecting beneath adjacent sections and spaced downwardly therefrom for engaging the adjacent sections when the first sections are elevated to the desired extent.

8. A grate comprising a plurality of loosely connected concentric sections, a post member connected to the center section, a hand lever connected to the post section for elevating the same to lift the grate sections and open the same, and means on said sections for interlocking the same for rotary movement.

9. A grate comprising a plurality of concentric loosely connected sections, an elevating handle connected to the middle section for lifting it and for consecutively lifting the remaining sections of the grate, said handle being adapted to be oscillated laterally for turning the center section, and interlocking means on the sections for vibrating the same in a circular path.

10. In a furnace, the combination of a casing, a support within said casing, and a grate rotatably engaging said support, said grate comprising inner and outer sections and intermediate members, interlocking connections between said sections and intermediate members arranged to limit but permitting relatively rotary movements therebetween, and means for rotating one of said sections.

11. In a furnace, the combination of a casing, a support within said casing, and a grate rotatably engaging said support, said grate comprising inner and outer sections and intermediate members disposed in concentric relation, one within the other, and movable vertically and rotatively relative to each other, interlocking connections between said

sections and members arranged to limit their vertical and rotative movements, and means for reciprocating and oscillating one of said sections.

12. In apparatus of the class described, the combination of a casing forming a fire box, an ash chamber and a heating chamber, a grate for fuel, said grate comprising a plurality of concentrically arranged members arranged to be disposed in a common horizontal plane or in stepped relationship, means for supporting said members independently in a horizontal position, sets of devices carried by each of said members arranged to limit their movement relatively one to another in either direction, and means acting on one of said members to move one or more thereof into stepped relation and to return them to normal position.

13. In apparatus of the class described, the combination of a casing forming a fire box, an ash chamber and a heating chamber, a grate for fuel, said grate comprising a plurality of concentrically arranged members arranged to be moved vertically into stepped relationship, one relative to another, and also angularly, each relative to the other, devices carried by said members arranged to limit either of said movements, and means for moving said members vertically or angularly.

14. In apparatus of the class described, the combination of a casing forming a firebox, an ash chamber and a heating chamber, a grate for fuel, said grate comprising a plurality of concentrically arranged members arranged to be moved vertically into stepped relationship, one relative to another, and also angularly, each relative to the other, devices carried by said members arranged to limit either of said movements, and means for moving said members vertically or angularly, said moving means comprising a vertical shaft, a sleeve rotatably and slidably mounted on said shaft and connected with one of said members and an operating device connected to said sleeve.

In testimony whereof, I have hereunto subscribed my name.

CHARLES W. THOMAS.
